UNITED STATES PATENT OFFICE.

JOHN PRESSLEY COLEMAN, OF EDGEWOOD, PENNSYLVANIA, ASSIGNOR TO THE UNION SWITCH AND SIGNAL COMPANY, OF SWISSVALE, PENNSYLVANIA, A CORPORATION OF PENNSYLVANIA.

RAILWAY-SIGNAL.

SPECIFICATION forming part of Letters Patent No. 745,308, dated November 24, 1903.

Application filed December 6, 1902. Serial No. 134,132. (No model.)

To all whom it may concern:

Be it known that I, JOHN PRESSLEY COLEMAN, a citizen of the United States, residing at Edgewood, in the county of Allegheny and State of Pennsylvania, have invented certain new and useful Improvements in Railway-Signals, of which the following is a specification.

My invention relates to railway-signals, and particularly to that class of railway-signals in which the motive power therefor is in the form of fluid-pressure.

I will describe a railway-signal embodying my invention and then point out the novel features thereof in claims.

In the accompanying drawings, Figure 1 is a view, partly in elevation and partly in vertical section, of a railway-signal embodying my invention. Fig. 2 is a detail view, partly in vertical section, showing some of the parts of Fig. 1 in a different position. Fig. 3 is a detail view showing in elevation some of the parts of Fig. 2, but in a plane of view at right angles to the plane of view of Fig. 1. Fig. 4 is a detail sectional view of a part comprised in the railway-signal. In Fig. 1 I have diagrammatically illustrated a section of railroad-track and such apparatus and circuits to show how the railway-signal of Fig. 1 may be automatically controlled by the movement of a train or trains over a section of railroad-track.

Similar letters of reference designate corresponding parts in all of the figures.

I will premise that wherever I herein use the term "signal" I mean a visual signal device which by its position relatively to its support or by its color gives indication of the service condition of the railroad-track or section of railroad-track which it governs. Also wherever I herein use the term "fluid-pressure" I mean a liquid or gas under pressure. I preferably employ a gas. Any gas may be employed—as, for example, air or carbonic acid gas—and under any pressure which is sufficient or more than sufficient to operate the apparatus for moving the signal. If the pressure of the gas is above that required for the operation of the apparatus for moving the

signal, reducing-valves may be employed in 50 their proper places.

Referring now to the drawings, A designates a visual signal device, here shown as being of the semaphore type, and comprising, as usual, a blade a and a counterweight a', which moves 55 the blade to one position of indication, generally to a horizontal position of indication, when the signal device is free to move—that is, when the signal device is not held by any agency in a position indicating "caution" or 60 "safety." The signal device is therefore biased to one position of indication, generally the horizontal position, indicating "danger." The signal device is pivoted, as usual, on a post or other support, and it is moved 65 from one position of indication to another, generally from the horizontal position to a position indicating "clear" or "safety," through the agency of a rod B. One end of the rod is operatively connected with the signal device, and the other end is operatively connected with the fluid-pressure mechanism or apparatus which is designed to move the signal device from one position of indication to another. 75

D designates the fluid-pressure mechanism for moving the signal from one position of indication to another. It is here shown as being in the form of a motor consisting of a piston d and a cylinder d', within which the piston moves. Fluid-pressure for operating the mechanism is here shown as being supplied from a tank or reservoir E, which may be of any size or capacity, or there may be a plurality of such tanks or reservoirs. The 80 pressure of the gas may be maintained in the tank or reservoir in any desired manner. In the case of carbonic-acid gas or any other similar gas being employed to operate the fluid-pressure mechanism, it is preferable that the 85 tank or reservoir be separately charged and afterward connected with the fluid-pressure mechanism. Instead, however, a charging pipe or pipes (see dotted lines, Fig. 1) may be connected with the tank or reservoir and 90 the gas under pressure supplied through such pipe or pipes from any suitable source. Any 95 number of individual tanks or reservoirs may

be supplied with the fluid-pressure from a single source through one or a number of pipelines. The fluid-pressure passes from the tank E to the fluid-pressure mechanism through a 5 pipe or conduit e, which is controlled by an electrically-operated valve device D', through a passage e', which is controlled by a second electrically-operated valve device D², and through a passage e³ to the cylinder d' of the 10 motor. The valve devices D' and D² may conveniently be substantially of the form and arrangement illustrated and described in United States Patent No. 357,109, issued February 1, 1887, for electrical interlocking mechanism for 15 switches and signals, to George Westinghouse, Jr., to which patent reference may be had for the details of construction and operation. It is only necessary to here state that each electrically-operated valve device has the 20 functions of opening the supply of fluid-pressure when the magnet comprised in the device is energized and of closing the supply of fluid-pressure when said magnet is de-energized and opening an exhaust port or passage e¹¹ to the 25 atmosphere. (See Fig. 4.) Any electrically-operated valve device having these functions may be employed.

In this invention the fluid-pressure mechanism is designed only to move the signal 30 device from one position of indication to another, preferably from the danger position to the clear position. This is accomplished, as here shown, by a single stroke of the piston of the fluid-pressure mechanism. After 35 the signal device has been moved by the fluid-pressure mechanism it is locked in the position in which it has been moved by means hereinafter described, and at or about the time the signal device is locked in the position to which it has been moved the valve 40 controlling the supply of fluid-pressure to the fluid-pressure mechanism is operated to cut off further supply to the fluid-pressure mechanism. As that fluid-pressure employed for 45 operating the fluid-pressure mechanism is of no further use, it is desirable that it be permitted to escape from the apparatus, and in the present instance the valve controlling the supply of fluid-pressure acts to open a port 50 or passage through which the fluid-pressure used for operating the fluid-pressure mechanism may escape to the atmosphere. It is obvious that a second valve suitably operated may be employed for this purpose. When it 55 becomes necessary that the signal device shall give an indication different from that given in the position to which it has been moved by the fluid-pressure mechanism and locked, the said means for locking the signal device 60 are rendered ineffective, leaving the signal device free to be moved by the counterweight acted upon by gravity.

The means for locking the signal device in the position to which it has been moved by 65 the fluid-pressure mechanism are here shown as comprising a fluid-pressure mechanism

the supply of fluid-pressure to which is electrically controlled and a locking device operated by said fluid-pressure mechanism.

D³ designates the fluid-pressure mechanism, 70 here shown as comprising a diaphragm d², which is held at its peripheral edge by a cap-plate or cover d³ for the chamber d⁴, in which the diaphragm is located. One side of the diaphragm is in communication through a 75 port or passage e⁴ with the passage e', so that the fluid-pressure may act upon it.

d⁷ designates a projection carried by the dia- 80 phragm through which the motion of the dia- phragm in one direction is communicated to a lever c⁷, which is hinged at one end.

The supply of fluid-pressure to the fluid- 85 pressure mechanism D³ is under the control of the electrically-operated valve device D'.

C designates the locking device, and as 85 here shown it comprises a pawl c³ and a lever c⁴ in the form of a bell-crank which engages the pawl c³. The pawl c³ is pivoted at one of its ends on a pin c¹², carried in a yoke portion c, formed in the rod B, preferably at its lower 90 end, and it is provided with a toe portion c¹³, which is adapted to engage the lever c⁴. The lever c⁴ is pivoted on a pin c², the ends of which are suitably held in some fixed part of the railway-signal—as, for example, the casing 95 C'. The lever c⁴ is also provided with a roller c⁵, suitably journaled in the lever and with which the pawl c³ engages, and with a stop c⁶, here shown as being the end of the lever which abuts against the rod B or the 100 casing C' to limit the movement of the lever in one direction. The lever c⁴ is moved on its pivot in one direction through the agency of a rod c⁸, one end of which is connected to the lever c⁴ and its other end to the lever c⁷. The 105 side members of the yoke c are provided with longitudinally-extending slots c', through which the pin c² extends. These slots permit of the rod B and its connections moving independently of the pin c² and the lever c'. 110 The effective position of the locking device is shown in Fig. 1. In this position the rod B, the yoke c, and the pawl c³, under the influence of the counterweight c', act downwardly to restore the piston d to the bottom of the 115 cylinder. Such action, however, is prevented by the lever c⁴, which is engaged by the pawl through the roller c⁵ so long as pressure exists under the diaphragm. By reason of the 120 relation of the journal of the roller c⁵ to the pivots c¹² c², it lying outside of a line drawn through the pivots c¹² c², the weight of the 125 signal and connected parts (rod B, &c.) is transmitted through the pawl c³ to the periphery of the roller c⁵ and through its journal to the center c² of the lever c⁴ and tends to force the lever c⁴ outward on its center c² and also to force the pawl c³ outward with the lever c⁴ to bring the toe portion c¹³ into engagement with the lever c⁴. The pawl c³, roller c⁵ and 130 its journal, and the lever c⁴ form, in effect, a toggle-joint. When the pressure is relieved

from under diaphragm, the lever c^4 moves outward on its pivot c^2 and with it the pawl c^3 , thus bringing the toe portion c^1 against the lever c^4 . In consequence of this the roller c^5 is moved from under the pawl and revolves on its journal and ceases to support the pawl, which swinging clear of the lever c^4 and roller c^5 descends and forces the piston to the bottom of the cylinder. The parts are then 5 in the position shown in Fig. 2, and the signal device is in the horizontal or danger position of indication. When fluid-pressure is again admitted under the diaphragm and to the cylinder d' , the roller c^5 is again moved 10 to the position shown in Fig. 1, stop c^6 limiting its movement, and the piston moves the rod B upward, and with it the pawl c^3 , which moves past the roller and is afterward moved 15 over the roller by the spring c^9 . At about 20 this time the fluid-pressure is cut off from the cylinder, but maintained under the diaphragm. The pressure being removed from under the piston, the parts moved by the piston settle down and finally assume the position 25 shown in Fig. 1.

In order to provide for cutting off the supply of fluid-pressure to the fluid-pressure mechanism D after it has moved the signal device to the clear position of indication, so 30 that it is or may be locked, I may employ a switch device or circuit-breaker to open the circuit through the valve device D^2 . CB designates such a device, and it is preferably 35 positively operated in two directions by a movable part or parts comprised in the railway-signal, thus having the railway-signal automatic in its operation of cutting off the supply of fluid-pressure. The circuit-breaker CB is here shown as comprising a movable 40 arm h , a portion of which h' may be of insulating material or of material suitably insulated from another portion h^2 , which latter portion is in electrical connection with a binding-post h^3 . The arm h is so mounted that it will be 45 prevented by friction or other means from moving except when operated by said movable part or parts. The arm h is adapted to make contact, and thus close a circuit, with a spring h^4 , in electrical connection with a binding- 50 post h^5 . The binding-posts h^3 and h^5 are in the present instance suitably insulated from their support. The arm h is moved to break contact with the arm h^4 and open a circuit including the electrically-operated valve device 55 D^2 when moved in one direction and to make contact and close the said circuit when moved in the opposite direction. The arm is moved by the piston d to open the circuit and by a pin or projection h^6 , carried by the rod B , to 60 close the circuit. The circuit through the electrically-operated valve device is preferably not opened until after the pawl c^3 has been moved past the roller c^5 and all the parts comprised in the locking means are in position 65 to effectually lock the signal device in the clear position, and the circuit is preferably

not closed until after the piston has reached or nearly reached the bottom of the cylinder.

In order that the railway-signal may be automatically controlled by the movement of a 70 train over the railroad-track or section of railroad-track which the railway-signal governs, I employ the armature of the track-relay to open and close the circuits through both the valve devices D' and D^2 . In Fig. 1 I have diagrammatically illustrated a section of track and the usual circuits and apparatus connected therewith for controlling a circuit, including the valve devices D' and D^2 . T designates the parallel lines of rail-sections which 75 constitute the railroad-track, TB the track-battery, the poles of which are electrically connected with the parallel lines of rail-sections, and TR the track-relay magnet, the terminals of the winding of which are also 80 electrically connected with the parallel lines of the rail-sections. It will be understood that when no train or pair of wheels is on the parallel lines of rail-sections and when there is no break in the electrical continuity of the 85 rail-sections or the electrical connections between the rail-sections and battery or rail-sections and relay the current from the battery TB will flow through the relay-magnet TR , thus attracting its armature r and 90 holding it in contact with a point or plate 1. When a train or pair of wheels is on the parallel lines of rails, it acts as a short circuit for the battery TB , thus shunting the current from the relay-magnet TR , which 95 then becomes deenergized and allows the armature r to fall away from and break the contact at 1 and against a point or plate 2. Preferably with the circuit-breaker CB closed when the armature r is attracted to the track 100 relay-magnet TR and it makes a contact at 1 a circuit will be closed through the magnets of both the valve devices. The circuit for the magnet of the valve device D' , starting from the battery Z , is wire 3, armature r , 105 contact-point 1, wire 4, magnet of the valve device D , and wire 5 back to battery. The circuit for the magnet of the valve device D^2 , starting from the battery Z , is wire 3, armature r , contact-point 1, wires 4, circuit 110 breaker or switch CB , wire 6, magnet of valve device D^2 , and wires 7 and 5 back to battery Z . It will be observed that the armature r is common to the circuit of both magnets and is, 115 in effect, a circuit-breaker. When it is not 120 against contact-point 1, the circuits through the magnets of both the valve devices will be open.

The operation of a railway-signal having my improvement is as follows: When the 125 railway-signal is in service and no train is on the railroad-track or section of railroad-track which the railway-signal governs and the track-circuit is complete, the parts comprised in the railway-signal are in the position 130 shown in Fig. 1, the signal device being in the clear position. In this position it will

be seen that the piston d of the motor engaged the arm h of the circuit-breaker CB and moved it to break its contact with the plate h^4 , and thus open the circuit through 5 the magnet of the valve device D^2 , the magnet of which being deenergized moves its valve to stop the flow of fluid-pressure to the cylinder d' and open an exhaust for any fluid-pressure in the cylinder to the atmosphere. 10 The circuit of the magnet of the valve device D' , however, is still complete, and the fluid-pressure therefore will be free to act under the side of the diaphragm of the fluid-pressure mechanism D^3 , which in turn holds the 15 lever c^7 in an elevated position and the roller c^5 of the bell-crank lever under the latch c^3 to have the locking device C in its effective position. Should, however, a train enter the railroad-track or section of railroad-track 20 controlled by the railway-signal, the track relay-magnet will be deenergized, as hereinbefore explained, and the armature r will fall away from contact-point 1, thus opening the circuit of the magnet of the valve device D' . 25 Fluid-pressure will then be cut off from the motor D^3 , and the locking device will then become ineffective and permit the counterweight to move the signal device to a position indicating "danger" in the manner herein- 30 before described. The parts of the locking device and the fluid-pressure mechanism D will then be in the position shown in Fig. 2, and the piston d of the fluid-pressure mechanism D will have moved to the lower end of 35 the cylinder to be again acted upon by the fluid-pressure when the magnet of the controlling device D^2 is again energized. When the piston d moves toward the bottom of the cylinder, the arm h of the circuit-breaker CB 40 is again operated, but this time by the pin h^6 , to close the circuit of the valve device D^2 , thus leaving the only break in the circuit of the valve device D^2 at contact-point 1. As soon as the railroad-track or section of rail- 45 road-track is clear of a train or pair of wheels of the train and the current from the battery TB can again flow through the track relay-magnet TR the armature r will again move against contact-point 1, and the circuit will 50 then be complete through the magnets of both valve devices. When this is done, fluid-pressure will then be admitted to both fluid-pressure mechanisms to operate them and have their parts and the parts of the railway- 55 signal again assume the position shown in Fig. 1.

What I claim as my invention is—

1. In a railway-signal, the combination of 60 a signal device, a fluid-pressure mechanism operatively connected therewith for moving the signal device from one position of indication to another position of indication, a second fluid-pressure mechanism and a locking device operated thereby for locking the signal device to the position of indication to 65 which it has been moved by said first-mentioned fluid-pressure mechanism, and a plu-

rality of electrically-operated valves for controlling the supply of fluid-pressure to said fluid-pressure mechanisms. 70

2. In a railway-signal, the combination of 75 a signal device, a fluid-pressure mechanism operatively connected therewith for moving the signal device from one position of indication to another, a locking device for locking the signal device in the position to which it has been moved, a fluid-pressure mechanism for operating the locking device, a fluid-pressure supply, an electrically-operated valve for controlling the supply of fluid-pressure to both 80 the fluid-pressure mechanisms and an exhaust for the fluid-pressure mechanism operating the locking device, and an electrically-operated valve for controlling the supply of fluid-pressure to the fluid-pressure mechanism connected with the signal device and an exhaust 85 from such fluid-pressure mechanism.

3. In a railway-signal, the combination of 90 a signal device, a fluid-pressure mechanism for moving said signal device from one position of indication to another, a locking device, a second fluid-pressure mechanism for operating the said locking device, a fluid-pressure supply for said fluid-pressure mechanisms, an electrically-operated valve for controlling the supply of fluid-pressure to each 95 of said fluid-pressure mechanisms, an electric circuit and source of current for each of said electrically-operated valves, a circuit-breaker common to both of said circuits, and a circuit-breaker in the circuit of the electrically-operated valve of the fluid-pressure mechanism for moving the signal device. 100

4. In a railway-signal, the combination of 105 a signal device, a fluid-pressure mechanism for moving said signal device from one position of indication to another, a locking device, a second fluid-pressure mechanism for operating said locking device, a fluid-pressure supply for said fluid-pressure mechanisms, 110 electrically-operated valves for controlling the supply of fluid-pressure to said fluid-pressure mechanisms, a normally closed circuit for the valve controlling the supply of fluid-pressure to the mechanism operating the locking device, and a circuit for the valve controlling the supply of fluid-pressure to the mechanism for moving the signal device which circuit is adapted to be opened when the fluid-pressure mechanism is operated by the fluid-pressure. 115 120

5. In a railway-signal, the combination of 125 a signal device, a fluid-pressure mechanism for moving said signal device from one position of indication to another, a locking device, a second fluid-pressure mechanism for operating said locking device, a fluid-pressure supply for said fluid-pressure mechanisms, an electrically-operated valve for controlling the supply of fluid-pressure to each of said 130 fluid-pressure mechanisms, an electric circuit and source of current for each of said electrically-operated valves, and a circuit-breaker, operated by a moving part comprised in the

railway-signal, included in the circuit of the electrically-operated valve device controlling the supply of fluid-pressure to the second fluid-pressure mechanism, whereby the said circuit is opened when the signal device is in a "clear" position of indication and closed when the signal device is in a "danger" position of indication.

6. In a railway-signal, the combination of
10 a signal device, a fluid-pressure mechanism operatively connected therewith for moving the signal device from one position of indication to another, a valve for controlling the supply of fluid-pressure to said mechanism, said valve being adapted when it has cut off the supply of fluid-pressure to open the fluid-pressure mechanism to the atmosphere, means operated from the fluid-pressure mechanism for effecting a movement of the said valve to
15 20 have it cut off the supply of fluid-pressure after the signal device has been moved by the fluid-pressure mechanism, a locking device for holding the signal device in the position to which it has been moved, a fluid-pressure mechanism for operating the lock-

ing means and a valve for controlling the supply of fluid-pressure to the last-mentioned fluid-pressure mechanism.

7. In a railway-signal, the combination of
15 a signal device, a means operably connected with the signal device for moving it from one position of indication to another, and locking means for locking the signal device in the position to which it has been moved independently of the moving means, said locking
20 means comprising a pawl pivoted to and in the line of the connection between the motor and signal device, a lever pivoted on a fixed center and having provision for engagement with the pawl, and means operated by fluid-
25 pressure for rocking the lever on its pivot to engage the pawl after the signal device has been moved.

In testimony whereof I have signed my name to this specification in the presence of 45 two subscribing witnesses.

JOHN PRESSLEY COLEMAN.
